UNITED STATES PATENT OFFICE

170,794

COMBINED BOTTLE AND DISPLAY CARTON THEREFOR

Eric de Kolb, New York, N. Y., assignor to Helena Rubinstein, Inc., New York, N. Y., a corporation of New York

Application June 20, 1952, Serial No. 20,286

Term of patent 7 years

(Cl. D58—12)

To all whom it may concern:

Be it known that I, Eric de Kolb, a citizen of the United States of America, residing at 470 Park Avenue, New York city, in the county of New York and State of New York, have invented a new, original, and ornamental Design for a Combined Bottle and Display Carton Therefor, of which the following is a specification, reference being had to the accompanying drawing, forming part thereof.

In the drawing

Figure 1 is a front elevational view of a combined bottle and display carton therefor, showing my new design;

Figure 2 is a side elevational view thereof;

Figure 3 is a top plan view thereof; and

Figure 4 is a vertical cross-sectional view thereof.

The dominant feature of my design resides in the portions shown in full lines.

I claim:

The ornamental design for a combined bottle and display carton therefor, substantially as shown and described.

E. DE KOLB.
